(57) **CLAIM**

The ornamental design for a permanently folded pocket square, as shown and described.

DESCRIPTION

FIG. 1 is a perspective view of the permanently folded pocket square shown with environment.

FIG. 2 is a front elevational view thereof shown with environment.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof; and,

FIG. 8 is an alternate perspective view thereof shown with environment.

The broken lines shown in FIGS. 1 and 2 illustrate features of the article that form no part of the claimed design. The broken lines shown in FIG. 8 represent environmental structure outside the article that assist in showing how the claimed design may appear when worn; these lines form no part of the claimed design.
